UNITED STATES PATENT OFFICE.

LEO LEROY HENRY, OF CEDAR RAPIDS, IOWA, ASSIGNOR TO JULIAN E. JACKSON, OF CEDAR RAPIDS, IOWA.

DESIGN FOR A MEMORANDUM PAD.

Application filed April 3, 1925. Serial No. 13,004. Term of patent 14 years.

To all whom it may concern:

Be it known that I, LEO LEROY HENRY, a citizen of the United States, residing at Cedar Rapids, in the county of Linn and State of Iowa, have invented a new, original, and ornamental Design for a Memorandum Pad, of which the following is a specification, reference being had to the accompanying drawing, forming part thereof.

The figure is a perspective view of a memorandum pad showing my new design.

What is claimed is:

The ornamental design for a memorandum pad as shown.

LEO LEROY HENRY.
